DESIGN FOR A COMBINED GLIDER AND CRADLE

Ernest W. Worley, Kansas City, Kans., assignor to Consolidated Razor Blade Co., Inc., Jersey City, N. J., a corporation of New Jersey

Application June 24, 1942, Serial No. 107,333

Term of patent 7 years

To all whom it may concern:

Be it known that I, Ernest W. Worley, a citizen of the United States, residing at Kansas City, in the county of Wyandotte and State of Kansas, have invented a new, original, and ornamental Design for a Combined Glider and Cradle, of which the following is a specification, reference being had to the accompanying drawing, forming a part thereof.

Fig. 1 is a side elevational view of the combined glider and cradle, showing my new design.

Fig. 2 is a top plan view; and

Fig. 3 is an end elevational view thereof.

I claim:

The ornamental design for a combined glider and cradle, as shown.

ERNEST W. WORLEY.
